UNITED STATES PATENT OFFICE

JOHN M. SEELY, OF NEAR NEW CARLISLE, OHIO, ASSIGNOR TO THE CHAMPION COMPANY, OF SPRINGFIELD, OHIO, A CORPORATION OF OHIO

DESIGN FOR A METAL BURIAL VAULT

Application filed January 30, 1932. Serial No. 42,682. Term of patent 14 years.

To all whom it may concern:

Be it known that I, JOHN M. SEELY, a citizen of the United States, residing in the county of Clark, near the town of New Carlisle, and State of Ohio, have invented a new, original, and ornamental Design for a Metal Burial Vault, of which the following is a specification, reference being had to the

accompanying drawing, forming part hereof.

The figure is a perspective view of a metal burial vault, showing my new design.

I claim:

The ornamental design for a metal burial vault, as shown.

JOHN M. SEELY.
